UNITED STATES PATENT OFFICE.

FERNANDO COTERA, OF CENTRAL FELIZ, CUBA.

DOUBLE OIL-BURNER.

1,391,047.

Specification of Letters Patent. Patented Sept. 20, 1921.

Application filed July 5, 1919. Serial No. 308,900.

To all whom it may concern:

Be it known that I, FERNANDO COTERA, a citizen of the Republic of Cuba, and residing at Central Feliz, Province of Matanzas, Republic of Cuba, have invented certain new and useful Improvements in Double Oil-Burners, of which the following is a specification.

The invention relates to oil burners, and more particularly to burners which are employed on locomotives.

It is an object of the invention to provide a burner which irrespective of the locomotion of the train is kept in lighted condition but with a decreased consumption of oil and consequently with a smaller flame when the train is stopping, thereby obviating the necessity of extinguishing and relighting the flame.

20 A further object of the invention aims at the provision of double compartments through which the fuel may be selectively discharged, the compartments being of different capacity consonant with the intention 25 of maintaining a large or small flame.

A further object entails the provision of double compartments for the issuance of steam whereby a greater or smaller amount of steam may be discharged to effect the 30 injector action in the fuel compartments with which said steam compartments co-act.

Other objects embrace the provision of suitable valves for bringing one or the other sets of compartments into action; and the 35 means for adjusting the openings through which the oil and steam issue.

To the accomplishment of the objects stated and others that will become apparent as the description proceeds, a preferred embodiment of the invention is disclosed in the accompanying drawing, described in the specification, and specifically pointed out in the appended claims.

In said drawing:

45 Figure 1 is a longitudinal section of a burner constructed in accordance with my invention, the section being taken on line 1—1 of Fig. 2;

Fig. 2 is an end view of the device from 50 the right as viewed in Fig. 1;

Fig. 3 is a cross-section on the line 3—3 of Fig. 1, and

Fig. 4 is a horizontal section of the device through the fuel containing compartments.

55 Fig. 5 is a horizontal section of the device through the steam compartments.

Referring to the various figures of the drawing, 1 generally designates the burner, which comprises four compartments 2, 3, 4, and 5, respectively, and separated from one another by walls 6, 7, 8, and 9. As indicated more particularly in Fig. 3, the two upper compartments 2 and 3 are of a larger cross-section than the two lower compartments 4 and 5, and again the compartment 2 is larger 60 than the compartment 3, and similarly the compartment 4 has a larger cross-section than compartment 5. The upper compartments, at the right hand side, as viewed in Fig. 1, are formed with openings 10 through 70 which the fuel fed into the upper compartments may discharge. In order to regulate the discharge opening 10 a disk valve 11 is secured to the end face of the device and reciprocating in a groove. The valve is secured to the device by a threaded member 12, which extends through a slot 13 in the valve 11, whereby the position of the valve with respect to the discharge opening may be varied to more or less restrict the discharge 75 opening. The lower compartments 4 and 5 through which steam is discharged are equipped with openings 14, and slide valves 15, of a similar construction as the valves 11, are provided to adjust the discharge 80 orifice of the lower compartments. 85

As indicated in Fig. 4, a conduit 16 serves to supply fuel, such as oil or petroleum, to the compartments 2 and 3 to which end the conduit 16 is formed with a bypass 17, which 90 leads to the compartment 3, while the pipe 16 opens into the compartment 2. Pipes 16 and 17 are equipped with a valve 18 which has ports 19 and 20 which respectively extend in horizontal and vertical direction so 95 as to selectively control the passage through the pipes 16 and 17. As shown in Fig. 4, the valve 18 permits the passage of the fuel through the pipe 16 into the compartment 2, and in order to disconnect the fuel supply to 100 the compartment and to feed the smaller compartment 3, the valve 18 is rotated about its longitudinal axis until the port 20 assumes a horizontal position whereas the port 19 extends vertically. The steam compartments 4 and 5 are supplied with steam by means of a pipe 27 which is provided with a bypass 21, leading into the compartment 5, while the pipe 27 opens directly into the pipe 23 in communication with the compartment 4. A valve 24 is interposed in the pipes 21 and 23, and is provided with spaced 105 110

- apertures 25 and 26, whereby alternately communication is established between the pipe 27 and compartments 4 and 5, respectively. To this end, the apertures 25 and 26 are arranged in the same manner as is described, with respect to valve 18.
- The operation of the device is thought to be obvious: When the train is in motion and it is desired that the burner have a large flame the valve 18 is arranged as shown in Fig. 4, and the valve controlling the supply of steam is placed in the same position so that simultaneously fuel may enter the compartment 2 while steam enters the compartment 4. The steam issuing at the outlet opening 14 creates an injector action in the compartment 2 causing the discharge of the fuel in the form of a jet, which, when lighted, maintains a large flame. If the train comes to a standstill and it is not desired to maintain such a large flame, it is unnecessary to extinguish the flame entirely as has been the practice followed hitherto, but the valve 18 is rotated until the passage through the pipe 16 is closed and the passage through the pipe 17 opened, so that fuel discharges through the compartment 3, which is of smaller capacity and hence supplies only a small amount of fuel necessary for the maintenance of a small flame. Together with the rotation of the valve 18 the valve for the steam supply is actuated so that steam is issued through the compartment 5. The flame will then shift transversely and will decrease in size due to the decreased supply of fuel. Attention is called to the fact that the compartments are of sufficient capacity to maintain a flame during the interval between the closing of one compartment and the opening of another. If the flame is not of a desired size or the operation of the device not satisfactory, then the valves for the discharge openings of the compartments may be adjusted.
- While the drawing discloses an embodiment of the invention it is of course obvious that many alterations and changes may be made without departing from the spirit of the invention, and it is therefore not my intention of confining myself strictly to the details as shown but to include all changes, modifications, alterations, and substitutions constituting departures within the purview of the invention as indicated by the appended claims.
- I claim:
1. In an oil burner, a plurality of independent compartments for the discharge of fuel, means for creating an injector action in said compartments, and means common to both of said compartments for selectively placing one of said fuel compartments in operation and the other out of operation.
  2. In an oil burner, a plurality of independent compartments of varying capacity for the discharge of fuel, means for creating an injector action in said compartments, and means arranged outside of said fuel compartments for selectively placing said fuel compartments in operation.
  3. In an oil burner, a plurality of independent compartments for the discharge of fuel, and means extraneous of said fuel compartments for selectively creating an injector action in one of said compartments and placing the other compartment out of operation.
  4. In an oil burner, a plurality of independent compartments for the discharge of fuel, a plurality of steam compartments co-acting with said fuel compartments for creating an injector action therein, and means extraneous of said fuel compartments for selectively placing coacting fuel and steam compartments in operation.
  5. In an oil burner, a plurality of independent compartments having openings for the discharge of fuel, means for creating an injector action in said compartments, means extraneous of said fuel compartments for selectively placing said fuel compartments in operation, and means for adjusting said compartment openings.
  6. In an oil burner, a plurality of independent compartments having openings for the discharge of fuel, a plurality of compartments having openings for the discharge of steam coacting with said fuel compartments for creating an injector action therein, means extraneous of said fuel compartments for selectively placing coacting fuel and steam compartments in operation, and means for adjusting the openings of said fuel and steam compartments.
  7. In an oil burner, a plurality of independent compartments having openings for the discharge of fuel, a plurality of steam compartments coacting with said fuel compartments for creating an injector action therein, means for supplying fuel and steam to respective compartments, and valves common to said fuel and steam compartments, respectively for selectively placing coacting fuel and steam compartments in operation.

In witness whereof I affix my signature. 115
FERNANDO COTERA.
